DESIGN FOR A VACUUM TUBE

William W. Eitel, San Bruno, and Jack A. McCullough, Millbrae, Calif., assignors to Eitel-McCullough, Inc., San Bruno, Calif., a corporation of California

Application May 19, 1942, Serial No. 106,948

Term of patent 14 years

To all whom it may concern:

Be it known that we, William W. Eitel and Jack A. McCullough, citizens of the United States of America and residents, respectively, of San Bruno and Millbrae, county of San Mateo, State of California, have invented a new, original, and ornamental Design for a Vacuum Tube, of which the following is a specification, reference being had to the accompanying drawing, forming part thereof.

Referring to the drawing:

Figure 1 is a plan view of the vacuum tube, showing our new design.

Figure 2 is a front elevational view of the tube; and

Figure 3 is a side elevational view of the same.
We claim:

The ornamental design for a vacuum tube, substantially as shown.

WILLIAM W. EITEL,
JACK A. McCULLOUGH.
